Hot Air Furnace.

No. 65,967.

Patented June 18, 1867.

United States Patent Office.

CHARLES W. TROTTER, OF ROCHESTER, NEW YORK, ASSIGNOR TO "GOMMENGINGER AND TROTTER," OF THE SAME PLACE.

Letters Patent No. 65,967, dated June 18, 1867.

IMPROVEMENT IN FURNACES.

The Schedule referred to in these Letters Patent and making part of the same.

TO ALL WHOM IT MAY CONCERN:

Be it known that I, CHARLES W. TROTTER, of Rochester, in the county of Monroe, and State of New York, have invented new and useful improvements in Hot-Air Furnaces; and I do hereby declare that the following is a full and exact description thereof, reference being had to the accompanying drawings, and to the letters of reference marked thereon.

Plate I, Figure 1, represents a side view of my improved furnace.

Plate I, Figure 2, represents a transverse section of furnace.

Plate II, Figure 3, represents a top or horizontal view of main or outer body A, showing triangular flues *b b b* and *i i i*, also flanges *h h h*.

Plate II, Figure 4, represents a top view of inner body, with triangular flues *n n n*.

Plate II, Figure 5, represents a top view of my double radiator, with cover off, showing openings of smoke pipes entering the radiators, also double damper *k* and *l*, part way open.

Plate II, Figure 6, represents my double damper *k* and *l*.

The nature of my invention consists in an improvement in hot-air furnaces, by making the main body A surrounded by triangular-shaped flues, a part of flues to be connected with an inner body or air-chamber, and the remainder of flues are for conducting the smoke and gas around the inner body and to a double radiator above. The whole is so constructed as to give a very large amount of heating surface.

To enable others skilled in the art to make and use my invention, I will proceed to describe its construction and operation.

I construct the main body A, fig. 3, of my furnace of cast iron, with triangular flues *b b b* and *i i i*; I also attach flanges *h h h* on the outside of the main body A. These flanges *h h h* are cast separate, and can be attached or detached at will. The triangular flues *i i i* are open on the lower ends and on the outside of fire-pot; the upper ends are connected with the air-chamber or inner body (fig. 4) at *n n n n n*, for the purpose of conducting the air from the outside of fire-pot to the inner body or air-chamber, (fig. 4,) where it is quickly heated and rises to the top through a large opening. The triangular flues *n n n n n* on inner body (fig. 4) fit close on top of triangular flues *i i i* of main body A, with openings on inside of air-chamber (fig. 4.) The triangular flues *b b b* are connected with the fire and smoke, and made for the purpose of conducting the heat and smoke around the inner body to the double radiator above, thus giving a great deal of heat from the inner and outer bodies. The flanges *h h h* being attached on the outside of main body for the purpose of giving more heating surface, I use two tiers of short pipes for conducting the smoke and gas to the radiator above; one tier of smoke-pipes on the outside marked *d d d*, and one tier on the inside, *e e e*, as shown in figs. 1, 2, and 5, for the purpose of giving direct and indirect draught. The radiator (fig. 5) has two channels, one on the outside, and one smaller on the inside, which channels are united by connections at *o o*, seen in fig. 5. The direct draught and indirect draught are regulated by double dampers *k* and *l*, figs. 5 and 6. To get direct draught, the damper *k* will have to be closed, and the damper *l* to be opened; this is all done at once, as both dampers are connected to one rod *m*. By closing the damper *k*, the damper *l* will open, thus giving direct draught, and, by closing damper *l*, damper *k* is opened; in this the smoke will have to pass from the outside channel to the inside channel to the smoke pipe *f* in rear, as shown in fig. 5. A great amount of heat is given by this double radiator. The red arrows represent the passage of air, and the black arrows represent the smoke and gas.

What I claim as my invention, and desire to secure by Letters Patent, is—

1. I claim the peculiar construction of the main body A, in connection with inner body *a*, with triangular flues *n n n n n*, all in the manner and for the purpose herein described.
2. I claim a double radiator, *C*, connections *o o*, and double damper *k* and *l*, with rod *m*, also two tiers of smoke pipes *d d d* and *e e e*, all in the manner and for the purpose herein set forth.

CHAS. W. TROTTER.
